UNITED STATES PATENT OFFICE.

RALPH LEE SHOUP, OF INDEPENDENCE, MISSOURI.

STATION-REGISTERING DEVICE.

Application filed October 15, 1925. Serial No. 62,689.

This invention relates to improvements in a registering or logging device for use upon radio sets and the like and to be used in place of the dials therefor for both turning the shaft of the respective instruments and for simultaneously operating an indicating end moving across a set dial arranged upon the upper portion of the device.

Another object of my invention resides in the provision of means for positioning removably secured cards upon the device immediately in front of the set dial and the pointer whereby stations may be marked upon the cards by pencils or like instrument by lines and afterwards whereby the cards after being marked may be filed alphabetically in completing a station registering device or log.

With the above and other objects in view, the invention further includes the following novel features and details of construction, to be hereinafter more fully described, illustrated in the accompanying drawings and pointed out in the appended claims.

25 In the drawings:—

Figure 1 is a front elevation of my invention as applied upon a portion of a radio panel.

Figure 2 is a side elevation thereof.

30 Figure 3 is a bottom plan view.

Figure 4 is a vertical sectional view taken through my invention as applied.

Figure 5 is a sectional view on the line 5—5 of Figure 4.

35 Figure 6 is a sectional view taken on the line 6—6 of Figure 5.

Figure 7 is a perspective of a top cover plate.

40 Figure 8 is a perspective of one of the logging or registering cards so marked by the pointer.

Referring to the drawings in detail, wherein like characters of reference denote corresponding parts, the reference character 10 indicates a fragmentary portion of a radio panel having openings 11 arranged therein for the reception of lugs or studs 12 provided upon the rear wall of a housing 13 for enclosing the above entitled invention.

45 Secured to the forward reduced end portion of a shaft 14 operating an instrument (not shown) and extending through registering openings provided in the panel 10 and rear wall of the housing 13 is a collar 15 held rigidly thereto through the instrumentality of a set screw 16 extending an

appreciable distance therein through the bore thereof and engaging the reduced portion of the shaft 14 extending therein. The plates 17 are secured to the forward side of 60 the collar 15 and have a lug 18 and offset pointer or hand 19 extending from the periphery thereof at an appropriate point in its circumference, the purpose and utility thereof being presently apparent. 65

The upper portion of the rear wall of the housing 13 forms a set dial 20 thereon and is provided with spaced parallel vertically disposed channel portions or grooves 21 upon its opposite side edges for the reception of the corresponding ends or edges of 70 logging or registering cards 22 capable of being marked according to the inclination of the hand or pointer 19 and the abbreviation of the stations arranged adjacent the 75 mark at which point the station was picked up.

In order to provide an operating means for the hand or pointer 19, I provide an arcuate shaped plate 23 having its upper end pivotally secured to the lug 18 provided upon the plate 17 and its lower end correspondingly secured to the inner side of a substantially U-shaped member 24 having registering threaded openings provided 85 in the adjacent side walls thereof for the reception of a vertically disposed bolt 25 therein which, in turn, is inserted through the bottom of the housing 13 and has a collar 26 arranged thereon adjacent its lower 90 end within the housing 13 for preventing its dropping through the opening thus provided for its insertion through the bottom of the housing 13, while the upper free end thereof terminates in a reduced portion 27 for reception 95 within an opening provided in the inwardly extending end portion of an angular bracket 28 arranged within the housing to prevent any canting or accidental displacement of the bolt during the operation thereof. A knob 29 is secured to the lower free end of the shaft or bolt 25 beneath the bottom of the housing 13. 100

A semi-circular cover plate 30 terminating in outwardly and oppositely extending end portions 31 is arranged upon the upper portion of the housing 13 for enclosing the top thereof for preventing the accumulation of dust or other extraneous matter upon the working parts of the invention and in slight 110 spaced relation with respect to the forward side of the set dial 20 in order that sufficient

and ample space is provided for the lateral movement of the pointer or hand 19 across the face of the card 22 when positioned within the grooves or channels 21 provided upon the opposite side edges of the set dial 20. In the use and operation of the present invention, it is clearly apparent that when the shaft or bolt 25 is rotated in either direction upon the turning of the knob 29 that the U-shaped member 24 will be caused to travel in opposite directions thereon and in so doing, owing to its connection with the lug 18 through the instrumentality of the arcuate shaped arm 23, will move the plate 17 as a unit with the collar 15 whereby the shaft 14 will be rotated and the hand or pointer 19 will travel laterally across the face of a card 22 positioned within the grooves or channels 21 arranged upon the opposite side edges of the set dial 20 in order that the instrument, not shown, operated by the shaft 14 may be rotated to a desired position in bringing in a station while the hand or pointer 19 may serve as a guide in marking a desired portion of the card 22 so arranged as to the exact position at which the respective station was picked up after which the name of the station is marked opposite the end of the marking upon the card 22; and the cards afterwards catalogued and arranged in alphabetical order for the convenience of the radio operator in readily and easily picking up the station so desired.

It is to be understood that the shaft or bolt 25 does not of necessity need to be positioned in the manner described and illustrated in so far as the latter may be positioned upon either side of the shaft 14, in vertical or horizontal positions with respect to the panel 10 and housing 13, nor does the free end of the shaft or bolt 25 need be reduced upon one end, as indicated at 27 for reception within the apertured portion of an angular bracket 28 in so far as the upper end of the shaft or bolt may be received within an opening of sufficient size within the corresponding bracket 28 and having a collar provided upon its upper end for journaling the latter therein and hence not weakening the structure thereof due to any reduction in size.

The invention is susceptible of various changes in its form, proportions and minor details of construction, and the right is hereinafter reserved to make such changes as properly fall within the scope of the appended claims.

Having thus described my invention, what I claim is:—

1. A station registering device for use upon radio sets comprising a housing arranged upon the panel, and receiving a portion of a radio instrument shaft therein through the panel, a set dial integrally formed upon the upper portion of the hous-

ing against the panel, a collar fixed upon the forwardly extending end portion of the instrument shaft within the housing and having a pointer extending therefrom adjacent the set dial, and operating means included within the housing for rotating the collar and shaft for imparting a lateral movement to the pointer across the dial in registering the station so picked up.

2. A station registering device for use upon radio sets comprising a housing arranged upon the panel and receiving a portion of an instrument shaft therein through the panel, a set dial formed upon the upper portion of the housing against the panel and having grooves provided within its opposite side edges for the reception of index cards therein, a collar fixed to the forward end portion of the instrument shaft, a pointer mounted upon the outer side of the collar and adapted for lateral movement across the face of the index card, and operating means mounted within the housing and communicating with the collar for simultaneously rotating the collar with the instrument shaft for registering the station picked up by the instrument when the pointer registers with corresponding indicia included upon the index card.

3. A station registering device for use upon radio sets comprising a housing arranged upon the panel and receiving a portion of an instrument shaft therein through the panel, a set dial formed upon the upper portion of the housing and having channel portions provided upon its adjacent side edges for the reception of an index card therein, a collar fixed to the forward end portion of the instrument shaft within the housing, a plate arranged upon the forward side of the collar and having a lug and pointer extending therefrom, an arcuate shaped arm pivoted to the lug upon the plate, and operating means included within the housing and connected to the opposite end of the arm for simultaneously rotating the instrument shaft and imparting a lateral movement to the pointer across the index card.

4. A station registering device for use upon radio sets comprising a housing arranged upon the forward side of the panel and receiving a portion of the radio instrument shaft therein through the panel, a fixed dial formed upon the upper portion of the housing against the panel, a collar fixed to the forward end of the instrument shaft within the housing, a plate arranged upon the forward side of the collar and having an apertured lug extending from the periphery thereof, a pointer also extending from the periphery of the plate and adapted for lateral movement across the face of the set dial, an operating shaft mounted within the housing, means traveling upon the operating

shaft, and means connecting the apertured lug of the plate with the traveling means upon the operating shaft for simultaneously operating and rotating the instrument shaft and imparting the desired lateral movement to the pointer across the set dial.

5. A station registering device for use upon radio sets comprising a housing arranged upon the forward side of the panel 10 and receiving a portion of the radio instrument shaft therein through the panel, a fixed dial formed upon the upper portion of the housing against the panel, a collar fixed to the forward end of the instrument shaft 15 within the housing, a plate arranged upon the forward side of the collar and having an apertured lug extending from the periphery thereof, a pointer also extending from the periphery of the plate and 20 adapted for lateral movement across the face of the set dial, a threaded vertically disposed operating shaft journaled within the housing, a substantially U-shaped member having registering threaded open- 25 ings provided in the adjacent side walls thereof and adapted to travel upon the shaft, and an arcuate shaped arm pivotally connecting the apertured lug of the plate and substantially U-shaped member whereby the 30 shaft upon successive turning will impart like rotation to the instrument shaft and a desired lateral movement to the pointer across the face of the set dial.

6. A station registering device for use upon radio sets comprising a housing arranged upon the forward side of the panel 35 and receiving a portion of the radio instrument shaft therein through the panel, a fixed dial formed upon the upper portion of the housing against the panel, a collar fixed to the forward end of the instrument shaft 40 within the housing, a plate arranged upon the forward side of the collar and having an apertured lug extending from the periphery thereof, a pointer also extending from the 45 periphery of the plate and adapted for lateral movement across the face of the set dial, a threaded vertically disposed operating shaft journaled within the housing, a substantially U-shaped member having register- 50 ings provided in the adjacent side walls thereof and adapted to travel upon the shaft, an arcuate shaped arm pivotally mounted upon the apertured lug of the plate and substantially U-shaped mem- 55 ber whereby the shaft upon successive turns will impart like rotation to the instrument shaft and a desired lateral movement to the 60 pointer across the face of the set dial, and channelled portions provided within the adjacent side edges of the set dial for supporting index cards therein having indicia thereon relevant to the point at which the hand registered upon picking up a desired station.

In testimony whereof I affix my signature.
RALPH LEE SHOUP.
